UNITED STATES PATENT OFFICE.

KARL WEINEL, OF CHICAGO, ILLINOIS, ASSIGNOR TO FREYN, BRASSERT & COMPANY, OF CHICAGO, ILLINOIS, A CORPORATION OF MAINE.

OVERFLOW DRAIN AND WATER SEAL FOR GAS WASHERS.

Application filed September 8, 1919. Serial No. 322,586.

To all whom it may concern:

Be it known that I, KARL WEINEL, formerly a citizen of the German Empire, but who now has declared his intention of becoming a citizen of the United States, residing at Chicago, in the county of Cook and State of Illinois, have invented certain new and useful Improvements in an Overflow Drain and Water Seal for Gas Washers, 10 of which the following is a specification.

My invention relates to an overflow drain and water seal for gas washers and has particular reference to a drain which is secured to the lower end of a vertical gas washer 15 tower of the type shown in Brassert Patent No. 1,169,766 at two places in said tower one drain above and the other below the gas entrance pipe, the lower drain being capable of being closed when desired.

20 My invention has particular reference to means for carrying away the water used in washing the gas should the main drain from the washer tower become stopped or clogged, or if it should be desired to make repairs 25 on the main drain it can be closed and the water will pass out through the overflow drain.

30 A further object of my invention in addition to the provision of an overflow drain is the provision of a water seal for gas washers wherein the main drain can be closed by means of valves and the valve in the lower or overflow drain pipe closed, thus causing the water which drains down in the 35 bottom of the gas washer tower to rise to a point above the gas entrance pipe. This effectively closes the passage of the gas through the gas washer tower.

40 Another object of my invention is the provision of an overflow drain and water seal which is simple and efficient in operation and which can be easily attached to gas washer towers of the kind now generally in use for cleaning blast furnace gas.

45 These and other objects of my invention will be more fully and better understood by reference to the accompanying sheet of drawings, and in which:—

50 The figure is a view in elevation of the lower end of the gas washer tower showing my improved invention secured thereto.

55 Referring now specifically to the drawings, and in which like reference characters refer to like parts throughout, a gas washer tower 10 is shown having the usual cone-

shaped bottom 11 secured thereto, a trap 12 is secured to the lower end of the member 11 from which a main drain pipe 13 leads in the usual manner. A gas supply pipe 14 is shown for supplying gas to the washer tower 10. A drain pipe 15 is provided which is connected to the gas washer tower at two points, one above and the other below the gas entrance pipe 14, as hereinafter described. A T 16 is interposed in said pipe 15 and has an ordinary gate valve 17 secured thereto, a nipple 18 being provided which is secured to the wall of the gas washer tower 10 below the pipe 14. A short section of pipe 19 is secured to the T 16 and 60 through an L 20, a spool 21 and a nipple 22 forming a continuation of the pipe line to the gas washer tower, thus providing an exit above the pipe 14. Secured to the lower end of the pipe 15 is a T 23 with a 70 blind flange on one end and to which an L 24 is secured. A section of pipe 25 is secured to the L 24 and extends upwardly therefrom to which in any manner may be secured another section of pipe to direct the flow of water in any direction desired, as by a T 26 and an L 27, thus providing 75 a siphon arrangement so that a column of water will close the pipe 15 at all times and prevent the gas from the gas washer passing therethrough. A flush pipe 28 is provided which is secured to the pipe 15 and the main drain pipe 13, an ordinary gate valve 29 being secured to the pipe 28 so that it may be closed 80 if desired. The purpose of this pipe 28 is to flush out the lower end of the drain 15 if necessary, or to supply it with a sufficient amount of water so that the pipe will be closed up and prevent the gas 85 flowing therethrough and out of the gas washer tower 10.

90 The device is exceedingly simple in operation and it will be understood that the valve 17 is open during the normal operation of the gas tower. If, for any reason, the main drain pipe 13 should become stopped up, or if it is desired to make repairs in this pipe line the water will continue to rise into the gas washer tower and flow out through the pipe 18 and into the pipe 15, away from the gas washer tower 10. If it is desired to use the device as a water seal the valves of the main drain pipe 13 are closed and the valve 17 is also closed and thus the water which 95 100 105 110

is being supplied in the upper part of the gas tower passes down and collects in the bottom of the tower, continues to rise above the pipe 14 through which the gas is being supplied to the tower until it reaches the pipe 22, whereupon the water will pass upward through the pipe 22 and into the drain pipe 15. In the meantime, of course, the water having risen to a point above the gas supply pipe 14 has effectively closed this pipe and prevents the passage of gas through the gas washer tower. It will also be understood that without the provision of this overflow drain 18 should the main drain pipe 13 become stopped up the water would continue to rise in the gas tower and completely shut off the flow of gas therethrough; thus necessitating the shutting down of the blast furnace and the stopping of all operations until the drain pipe 13 could be cleaned out and the water drained out of the gas washer tower. It is necessary to provide water for the washing of the gas as it passes through the tower and if the drain pipe 13 should become stopped up it will cause the water to rise in the tower and effectively close the tower against the passage of gas therethrough.

While I have described more or less precisely the details of construction, I do not wish to be understood as limiting myself thereto, as I contemplate changes in form and the proportion of parts and the substi-

tution of equivalents as circumstances may suggest or render expedient without departing from the spirit or scope of my invention. 35

I claim:

1. In combination, a gas washer tower, an upwardly extending drain pipe connected to the bottom of said tower whereby a water seal is maintained at a predetermined height, a pipe connected to said tower and forming a gas inlet, and a drain pipe connected to said gas washer tower below the gas inlet and above the line of the water supply maintained in said tower, and having a siphon at the lower end of said drain pipe for maintaining a water seal. 40 45

2. In combination, a gas washer tower, an upwardly extending drain pipe connected to the bottom of said tower whereby a water seal is maintained at a predetermined height, a pipe connected to said tower and forming a gas inlet, a drain pipe connected to said gas washer tower below the gas inlet and above the line of the water supply maintained in said tower, and having a siphon at the lower end of said drain pipe for maintaining a water seal, and a second pipe connected to said siphon whereby a supply of water is maintained in said drain pipe at all times whereby the said pipe is closed against the passage of gas therethrough. 50 55

Signed at Chicago, Illinois, this 29th day of August, 1919.

KARL WEINEL.
